UNITED STATES PATENT OFFICE

2,177,666

COATING APPARATUS

Wilbur Le Roy MacKenzie, Beverly, and Ernest S. Nokes, Lynn, Mass., assignors to United Shoe Machinery Corporation, Borough of Flemington, N. J., a corporation of New Jersey

Application September 9, 1937, Serial No. 163,682

29 Claims. (Cl. 91—43)

This invention relates to coating apparatus and is herein illustrated as embodied in a machine for applying a stripe of coating material to the marginal portions of the bottoms of shoes and of the type illustrated in Letters Patent of the United States No. 2,100,341, granted November 30, 1937, on an application of W. L. MacKenzie.

The application of a stripe of coating material to the bottoms of shoes for the attachment of soles thereto presents substantial difficulties because of the character of the work to be coated, it being understood that this marginal portion of the bottom of a shoe does not lie in a single plane but traverses shoe material which is irregular and wrinkled. To such a surface it is desired to apply, in one or a plurality of parallel stripes, a continuous and uniform band of coating material, such as cement, and this has been successfully accomplished by means of the machine of the extruding type illustrated in the above-mentioned prior patent in which the application of cement under pressure is carried out by means of a rubber nozzle, the outlet end of which is maintained in continuous contact with the work. It has been found, however, that the character of the surface to be treated is such that nozzles made of rubber and rubber substitutes are subject to continual abrasion so that their life is not long. Furthermore, it is not practicable to immerse such nozzles in a solvent for the cement, during over-night and week-end periods, in order to keep the cement from hardening in the nozzle passages, without causing deterioration of the nozzle itself.

Accordingly, an important object of the invention is to provide, for a coating apparatus, a metal nozzle which will be flexible enough to accommodate the irregularities of the work and at the same time will deliver a continuous and uniform stripe or stripes of coating material.

These conditions have been met in the illustrated construction and in accordance with a feature of the invention, by providing a plurality of displaceable delivery members to the work-engaging feet of which the coating material is delivered through individual tubes, the arrangement being such that displacement of the individual delivery members is not interfered with by the tubes.

This desirable result has been reached in accordance with another feature of the invention by providing the feet of the delivery members with passages terminating in outlet openings and receiving yieldable tubes of capillary size,

the other ends of which are supported in communication with a supply of coating material under pressure. As illustrated, the tubes are individually yieldable and their delivery ends are slidably engaged in the passages of the feet of the delivery members which latter, as illustrated, have grooves extending forwardly in the feet and in which grooves the outlets of the passages open.

Still another feature of the invention resides in the provision of a solvent-containing cup positioned for the convenient reception of the nozzle when disconnected from its normal support. Preferably, and as illustrated, this cup has a cover provided with a slot into which the nozzle may be thrust and also provided with means for releasably clamping the nozzle to the cover.

These and other features of the invention will be best understood in consideration with the following description taken in connection with the accompanying drawings, in which

Fig. 1 is a side elevation of the machine, the supporting column being omitted;

Fig. 2 is an angular view of the solvent cup;

Fig. 3 is a side elevation, on a much larger scale, of a part of the machine including the nozzle and the feed roll;

Fig. 4 is an angular detail view showing a spring-supporting plate used in the nozzle;

Fig. 5 is an end view of the part of the machine shown in Fig. 3 and on a similar scale;

Fig. 6 is an angular detail view of the tube-holder plate used in the nozzle;

Fig. 7 is an angular view of some of the delivery members of the nozzle, showing these in separated positions, and

Fig. 8 is an angular view, in a different direction, of one of these members.

A machine of this type, shown in the above-mentioned MacKenzie patent, for applying a band of cement around the margin of the bottom of a shoe for use in the attachment of a sole thereto, comprises a frame 10; a portion of which is made hollow and provided with an integral side plate 12 and a removable plate 14 held in spaced relation thereto by shouldered bolts 16. On the frame is mounted a cement receptacle 20 supplied from an inverted can 22 and from this receptacle the cement is removed by means of a pump 24 and forced under pressure through a flexible hose 26 and a nozzle 28, whenever a valve 30 is opened. The pressure in the hose is indicated by a gage 32 and the valve 30 is under the control of the operator through connections embodying a treadle rod 34 and a

horizontal turn rod 36 which is constructed to be readily disconnected from the valve handle at 38 when it is desired temporarily to remove the nozzle, as will be later described. Work, such as 5 a shoe 40 mounted on a last 42 and having an upper overlaid at 44 on the insole 46, may be provided with a ridged metallic shank 48 and is held in inverted position in the hands of the operator. As thus held, its margin is presented 10 progressively to the nozzle 28, being moved forward with the assistance of a rubber-tired feed roll 50 driven by a mechanism (not shown) such as that found in the patented machine. This feed roll 50 is mounted on a carrier 52 which, 15 in its operative position, is held out by the operator to a limit defined by engagement of a portion of the carrier with a stop 54. In this position, the feed-roll carrier may be pushed inwardly against the tension of a spring (not shown), if 20 required by the contour of the shoe.

Such a machine may be provided with a nozzle-supporting arm 56. In this arm 56 there is clamped a rod 58 adjustable in and out with respect to the machine to position the band of 25 cement and supporting at its outer end a depending carrier 60. The upper end of this carrier is split and is gripped in the desired position on the rod 58 by means of pinch screws 62. This carrier is L-shaped and is forked at its lower end, 30 providing two horizontally projecting arms 64 and 66 (Fig. 3) which have supporting surfaces 68 and stop surfaces 69 to receive a nozzle body 70. This nozzle body fits snugly between the arms 64 and 66 and has lateral flanges 72 which rest on the supporting surfaces 68 (Fig. 5) and, when 35 the nozzle is brought into assembled relation to the machine, are pressed manually into an operating position determined by the stop surfaces 69. As thus mounted, the nozzle body is held in 40 position by a clamp lever 74 shaped like an inverted Y and mounted by means of a pivot pin 76 on the carrier 60 with its forked lower ends 78 resting on the upper sides of the flanges 72 of the nozzle body to grip them in position when 45 urged thereagainst by means of a hand screw 80 threaded in the carrier 60 and bearing against the upper end of this lever 74.

The application of a continuous and uniform band of cement to the bottom of a lasted shoe 50 involves numerous difficulties, partly because of the changing contour of the bottom surface as successive portions of the margin are treated and partly because of the irregular surface found and which results, for example, from the presence 55 of the shank piece 48 or from the wrinkles in the overlaid upper. These conditions were met successfully in applicant's earlier machine by means of a flexible nozzle of rubber or the like. Such nozzles maintain contact very well with the 60 surface to be treated but wear away rather rapidly and have to be replaced. Accordingly, the nozzle 28 disclosed herein is made of metal and is rendered flexible by being made up of a series of pivoted plate-like delivery members 81 assuming 65 various forms 82, 84 and 86 (Fig. 7), but each having a passage 124 (Fig. 5) terminating in an outlet or delivery opening 88 within a V-shaped groove 90 extending forwardly along the work-engaging surface of the foot 83 of said delivery 70 member. It will be noted that the members 82 and 86 are designed to be positioned at the outer sides of the series of members and, for this reason and in order that the width of the stripe of cement may be determined with some exactness, 75 these members have depending edges 92, 94 which

are somewhat longer than the corresponding inner edges 96, 98 so that they overcome any tendency for the cement to spread laterally. The inner edges 96, 98 are cut away at the corners 100 to permit the cement extruded through these members to spread laterally inward and to merge with the stripes of cement supplied through the members 84 in which the lateral side edges 102 are each provided with notches 104 for a purpose similar to the purpose of the notches 100. The 10 delivery of a continuous stripe or band of coating material is facilitated by the V-shaped grooves in the feet of the delivery members. These prevent the work from closing the outlets 88 and may be kept full of cement with only a 15 moderate pressure upon the cement. For most purposes, it is found desirable to position the sides of the grooves 90 at an included angle of substantially ninety degrees with one another but with some particular cements, however, it may be 20 found desirable to change the included angle between the sides to sixty degrees.

When assembled, the nozzle delivery members 81, of which seven are shown here, are positioned side by side, with the lateral faces at the upper 25 ends of the members in contact with one another and in order to facilitate assembly and disassembly of the nozzle, the members are mounted on a sleeve 110, thus making it easier to take them out, as a group, as for cleaning. It will be observed from Fig. 7 that the lower ends or feet of the members 84 are of full width as at the top but that the intermediate portions are thinned or relieved, as at 112 (Fig. 8) to reduce 30 friction and any tendency to stick together and 35 to facilitate the introduction of solvent, as will be later described. The outer members 82 and 86 are relieved only on the inner faces. The assembled members are pivotally mounted between two flanges 114 of the nozzle body and held 40 there by a removable headed pin 116 passing through the sleeve 110 and held in position by a cotter pin 118. It will be observed from Fig. 3 that the side flanges 114 of the nozzle body are cut away at 120 to reduce the friction between 45 the outer members and the body and to admit solvent. Downward movement of the members 81 below a predetermined level is prevented by contact of their upper ends 85 with the body 70.

Delivery of cement to the outlet openings 88 of the pivoted members is effected through a plurality of resilient, metallic, capillary tubes 122, the lower ends of which are slidably mounted in passages 124 in the feet 83, said passages terminating at exterior surfaces of the feet in 55 inlet openings adjacent to grooves 142 in the outlet openings 88. The lower ends of the tubes are thereby protected against injury from contact with the shoe and at the same time the freedom of movement of the members of the nozzle 60 is not reduced as the tubes can slide in the feet of these members and can bend slightly as the members are tilted by upward pressure of the work. These tubes are assembled in a tube-holder plate 126, their upper ends opening into 65 a recess 128 which, when the holder plate is mounted on the nozzle body and held there by screws 130, communicates with a passage 132 in said body. The upper end of the passage 132 opens into a passage 134 in the body 136 of the 70 valve 30. The lower end of this valve body 136 is attached by screws to the flanged upper face of the nozzle body 70. The various tubes 122 are fixed firmly in position in the holder plate 126 by solder 138 filling a previously formed groove 75

140 in the plate. Inasmuch as this groove is intersected by all the tubes 122, a single soldering process is all that is necessary to hold the various tubes in position and there is no danger of getting solder in the tubes. The introduction of the lower ends of the tubes 122 on the holder plate 126 into the upper ends of the passages 124 opening laterally, i. e., at the under sides, of the feet of the delivery members is facilitated by the provision of the semicircular grooves 142 in the under faces of the feet of the members 81 in alinement with the passages 124. With the feet positioned substantially in alinement, it is only necessary for a user of the machine to take the tube-holder plate 126 and, raising it, to press with the thumb the lower ends of the tubes into the grooves 142. Springs 150 bearing against the delivery members resist the upward pressure and facilitate the seating of the tubes in these grooves. Having pressed the tubes into the open grooves, the whole series of tubes may be entered in the passages 124 of the feet by a slight lateral movement of the tube-holder plate 126.

The feet of the various members of the nozzle 25 are held resiliently in contact with the work, in spite of irregularities therein, by means of the above-mentioned springs 150, here shown as made of wire, the lower ends of which are curved upwardly and rest in V grooves 152 (Fig. 8) 30 formed in the upper edges of the members. As with the tubes, these springs 150 are assembled in parallel positions in a spring-carrier plate 154 having a series of parallel grooves 156 in its lower face and a series of apertures leading upwardly into a groove 158. The upper ends of the springs are turned upwardly at substantially right angles and, passing through the apertures in this groove 158, are held in position therein by solder 160 filling the groove. It is easy, therefore, to position the spring-carrier-plate 154 with the lower ends of the springs resting in the grooves of the nozzle members and then to attach it to the nozzle body 70 by means of screws 162 (Fig. 5).

Any tendency of the pivoted members of the nozzle to be stuck together by the cement is avoided by supplying small quantities of solvent, suited to the cement employed, to the upper side of the assembled nozzle through a tube 164 supported on a bracket 166 which is attached to the side plate 12 of the frame, solvent being supplied through this tube, drop by drop, from a receptacle 168 similar in construction to the common sight-feed lubricating cup employed in many machines. The cup may be opened or closed by means of a finger piece 170 and the delivery of fluid regulated by a thumb nut 172.

When the machine is not to be in use for a substantial period, over night, for example, it is found convenient to immerse the nozzle in a bath of solvent and, to simplify and hence encourage this step, there is provided a solvent cup 174 (Figs. 1 and 2) having a bracket 176 enabling it to be detachably secured to the frame of the machine by means of a bolt 178 and a coacting wing nut 180. Solvent is kept at the desired level in this cup 174 by means of an inverted bottle 172 serving as a barometric feed therefor. A cover 184 is mounted on the cup by means of a pivot pin 186 and held firmly closed against it by a wing nut 188. This cover has a slot 190 just wide enough to receive the nozzle body 70, with the flanges 72 of the body resting on the adjacent top surfaces of the cover. The cover is provided with an upright 192 to which is pivoted a clamp

194 substantially like the clamp 74 on the machine and this may be used to grip the nozzle body to the cover when pressed into contact with the flanges 72 by a thumb screw 196. When the nozzle is not in the solvent cup, the opening provided by the slot 190 is closed by means of a pivoted flap 198. It will thus be seen that a convenient arrangement has been provided in such a position with respect to the attaching point of the flexible hose 28 that the nozzle may, by loosening the screw 80 of the clamp 74, quickly be separated from its carrier 60 and, after separating the valve rod 36 but without detaching the gage or the valve casing 136, may be swung into position in the solvent cup. The cover 184 will be tilted up about its pivot pin 186 to admit the nozzle delivery members to the cup, as the nozzle body is slipped into the slot 190, and will then be returned and fastened by the wing nut 188. The nozzle is then secured in the slot of the cover 184 of the solvent cup by the clamp 194 and, hence, there is no danger of damage to the feet of the delivery members of the nozzle by reason of contact with the bottom of the cup and the correct position of the nozzle with respect to the cup is assured.

In the operation of the machine, a piece of work is presented in inverted position, as indicated in Fig. 3, whereupon the operator depresses a treadle connected to the treadle rod 34, thus opening the valve 30, and cement is delivered by the pump 24 to the nozzle. At the same time, the feed-wheel carrier 52 is moved outwardly to bring the feed wheel 50 into contact with the side of the shoe and a progressive treatment of the margin of the bottom of the shoe is thus facilitated, it being understood that the operator supports the shoe at various angles necessary for the presentation of the uneven surface of the shoe to the nozzle, a uniform delivery of cement through the spring-pressed delivery members of the nozzle being effected as the shoe is moved along to present the bottom margin progressively to the nozzle. During this traversing movement of the work, the nozzle will accommodate itself to the varying surfaces of the shoe bottom by reason of the pivotal mounting of the delivery members. At the same time, each individual delivery member is narrow enough so that its lateral edges remain substantially in firm contact with a portion of the bottom to which it is delivering cement. This enables a continuous and uniform stream of cement to be delivered through each member and these streams or threads usually merge to form a stripe of substantial width.

Having described our invention, what we claim as new and desire to secure by Letters Patent of the United States is:

1. In a coating apparatus, a device for applying a stripe of coating material to a piece of work and comprising a displaceably mounted rigid delivery member having a foot provided with a passage terminating at outside surfaces thereof in an inlet opening and an outlet opening, and means for supplying coating material under pressure to said passage and comprising a flexible tube rigidly supported at its supply end and directly inserted at its other end in the inlet opening of said foot.

2. In a coating apparatus, a support, a series of separate delivery members movably mounted upon the support independently of one another and adapted to rest in contact with the work, and a series of flexible tubes secured in the support and arranged to be connected to a source of sup-

- ply, said tubes being individually connected to the delivery members.
3. In a coating apparatus, a device for applying a stripe of coating material to a piece of work and comprising a plurality of spring-pressed delivery members having passages terminating in outlet openings in the work-engaging ends thereof, and tubes severally, slidably engaging said passages.
- 10 4. In a coating apparatus, a device for applying a stripe of coating material to a piece of work and comprising a plurality of delivery members arranged side by side transversely of the width of the stripe, the delivery members having feet which are displaceable under pressure of the work, the feet of said delivery members having passages terminating in outlet openings, and means for supplying to said passages coating material under pressure and comprising a plurality of tubes fixed at one end, the other ends of said tubes being slidable in said passages thereby permitting displacement of said feet without interrupting the supply of coating material.
- 15 5. In a coating apparatus, a device for applying a stripe of coating material to a piece of work and comprising a plurality of displaceable plate-like delivery members having work-engaging feet, said members having passages extending through a portion of the length thereof and terminating in outlet openings in said feet, and means for supplying coating material under pressure to said delivery members and comprising a plurality of tubes rigidly secured at their inlet ends and entering the passages in said feet at their outlet ends.
- 20 6. In a coating apparatus, a device for applying a stripe of coating material to a piece of work and comprising a plurality of pivotally mounted delivery members the free ends of which are provided with work-engaging feet having passages terminating in outlet openings, resilient means for holding said feet in contact with the work, and means for supplying coating material under pressure to said feet and comprising a plurality of tubes terminating in said passages.
- 25 7. In a coating apparatus, a device for applying a stripe of coating material to a piece of work and comprising a plurality of pivotally mounted delivery members having work-engaging feet provided with forwardly extending grooves in their work-contacting surfaces, said feet having passages originating laterally thereof and terminating in said grooves, and means for supplying coating material under pressure and comprising tubes severally connected to said passages, said tubes being yieldable to permit movement of the feet.
- 30 8. In a coating apparatus, means for applying a stripe of coating material to a piece of work and comprising pivotally mounted work-contacting members having apertured feet, resilient means for holding said apertured feet in contact with the work, and means for supplying coating material under pressure to the individual feet and comprising tubes connected with said feet adjacent to their outlet ends and at points removed from their pivotal mounting.
- 35 9. In a coating apparatus, a striping tool comprising a plurality of members pivotally mounted side by side in a group substantially in contacting relation and having apertured feet to rest on a piece of work, resilient means for holding said work-contacting feet against the work, and means for supplying coating material under pressure to the apertures in said feet and comprising
- 40 individual resilient tubes rigidly supported at a point spaced from the pivot of said members and joined severally to said members at points adjacent to the outlet openings thereof.
- 45 10. In a coating apparatus, a plurality of individual coating-material-applying members having each an outlet opening adjacent to its point of contact with the work, said members being individually displaceable and spring pressed thereby to accommodate irregularities in the surface contour of the work, and means for supplying coating material to the outlets of said displaceably mounted members and comprising individual tubes leading from a fixed chamber to points on said members closely adjacent to the applying ends thereof.
- 50 11. In a coating apparatus, a device for applying a stripe of coating material to a piece of work and comprising a plurality of displaceable delivery members positioned side by side, and individual springs for said members secured at one end to a removable plate common to said springs.
- 55 12. In a coating apparatus, a device for applying a stripe of coating material to a piece of work and comprising a plurality of displaceable delivery members, a plurality of springs associated therewith, a spring plate having grooves to receive and position said springs, and means for holding said springs on said plate.
- 60 13. In a coating apparatus, a device for applying a stripe of coating material to a piece of work and comprising a plurality of displaceable delivery members, a plurality of springs associated therewith, and a spring plate having apertures receiving said springs and opening into a solder-filled groove.
- 65 14. In a coating apparatus, a device for applying a stripe of coating material to a piece of work and comprising a plurality of nozzle tubes, a plate having a recess in which said tubes open at their inlet ends, passages in said plate for the tubes, a transverse groove intersecting the passages between the recess and the outlet ends of the tubes, and solder in the latter groove securing the tubes.
- 70 15. In a coating apparatus, a device for applying a stripe of coating material to a piece of work and comprising a plurality of displaceable delivery members, substantially parallel springs associated with said members, a spring plate having spring-receiving positioning grooves, a groove transverse to said positioning grooves, and apertures opening into said transverse groove.
- 75 16. In a coating apparatus, a device for applying a stripe of coating material to a piece of work and comprising a plurality of nozzle tubes, a supporting plate therefor, a groove in the plate extending transversely of the tubes with both sides of the groove spaced from ends of the tubes, passages for the tubes intersecting the groove, and solder in the groove to secure the tubes.
- 80 17. In a coating apparatus, a device for applying a stripe of coating material to a piece of work and comprising a displaceable delivery member having a work-contacting foot provided with a passage terminating in an outlet in said foot, the other end of said passage opening laterally of said delivery member, and provided with an open groove having a surface in alignment with said passage to facilitate the insertion of a supply tube therein.
- 85 18. In a coating apparatus, a device for applying a stripe of coating material to a piece of work and comprising a plurality of pivoted delivery members, springs tending to hold said delivery members in alignment against a stop, passages

- through the ends of said delivery members opening laterally thereof, said members having open grooves in alignment with the passages, supply tubes for the delivery members supported in alignment with one another, and means for supplying coating material through said tubes. 5
19. In a coating apparatus, a device for applying a stripe of coating material to a piece of work and comprising a nozzle body, a plurality of delivery members displaceably mounted on said body, a bushing extending transversely of said delivery members to hold them in a group, and a pin passing through said body and said bushing to mount the members on the body. 10
- 15 20. In a coating apparatus, a device for applying a stripe of coating material to a piece of work and comprising a nozzle body, a plurality of delivery members displaceably mounted on said body, a bushing extending transversely of said delivery members to hold them in a group, a pin passing through said body and said bushing to maintain the members on the body, resilient means urging said delivery members in one direction, and individual supply tubes for said members. 20
- 25 21. In a coating apparatus, a device for applying a stripe of coating material to a piece of work and comprising a plurality of displaceable delivery members mounted side by side in substantially contacting relation, said delivery members having grooved, work-contacting feet, means to supply coating material to said grooves, said grooved feet being cut away at the leaving ends at those corners which are adjacent to another foot. 30
- 35 22. In a coating apparatus, a device for applying a stripe of coating material to a piece of work and comprising a plurality of displaceable delivery members mounted side by side in substantially contacting relation, said delivery members having grooved work-contacting feet, and means to supply coating material to said grooves, the outside members of the group having their outer edges longer than the inner edges. 40
- 45 23. In a coating apparatus, a device for applying a stripe of coating material to a piece of work and comprising a plurality of displaceable delivery members mounted side by side in substantially contacting relation, said delivery members having grooved work-contacting feet, and means to supply coating material to said grooves, said grooved feet being cut away at the leaving end at those corners which are adjacent to another foot, the outside members of the group having their outer edges longer than the inner edges. 50
- 55 24. In a coating apparatus, a frame member, a nozzle member having a portion resting against
- said frame member, a clamping lever fulcrumed on one of said members and engaging the other member, and means arranged to swing said lever to clamp the nozzle member against the frame member. 5
25. In a coating apparatus, a device for applying a stripe of coating material to a piece of work and comprising a nozzle support provided with adjacent angularly related surfaces, a nozzle body adapted to be positioned by engagement with said surfaces, and a pivoted, screw-operated clamp for holding said nozzle body against one surface. 10
- 15 26. In a coating apparatus, a device for applying a stripe of coating material to a piece of work and comprising a nozzle body, a nozzle support having forked ends which are spaced to receive and position a portion of the nozzle body, said body having laterally extending flanges supported on said forked ends, and a forked clamp 20 for pressing said flanges against said forked support. 20
- 25 27. In a coating apparatus, a device for applying a stripe of coating material to a piece of work and comprising a nozzle, means for applying coating material to said nozzle and comprising a flexible hose secured at one end to the machine and at the other end to the nozzle, means for supporting said nozzle in an operative position, a solvent cup secured to the machine and positioned to receive the nozzle when in inoperative position and without detachment of the hose connected thereto, and means for securing said nozzle in said cup. 30
- 35 28. In a coating apparatus, a device for applying a stripe of coating material to a piece of work and comprising a nozzle, means for supplying coating material under pressure to said nozzle including a flexible hose and a shut-off valve, an operator-controlled device for said valve separably connected thereto, a releasable clamp holding said nozzle in operative position, and a solvent cup on the machine within the reach of the hose, said cup being provided with a cover having a nozzle-clamping device whereby the nozzle may be disconnected from the valve-operating means, loosened from its support and then clamped in position in the solvent cup without disconnecting the hose. 40
- 45 29. In a coating apparatus, a device for applying a stripe of coating material to a piece of work and comprising a detachably supported nozzle, a solvent cup, a cover for said cup having a nozzle-receiving slot, a clamp for holding the nozzle in normal position upon the machine, and another 50 similar clamp on the slotted cover of the cup. 55
